UNITED STATES PATENT OFFICE.

MICHAEL HACKETT, OF GRIMES, IOWA.

ENGINE-VALVE.

1,182,677.

Specification of Letters Patent. Patented May 9, 1916.

Application filed July 19, 1912. Serial No. 710,381.

To all whom it may concern:

Be it known that I, MICHAEL HACKETT, a citizen of the United States, residing in Grimes, county of Polk, and State of Iowa, have invented a new and useful Improvement 5 in Engine-Valves, of which the following is a specification.

The object of my invention is to provide means, simple, strong, durable and practically inexpensive, in construction, of timing 10 the admission of gas into the cylinders of a multiple cylinder gasoline motor and also the timing of the opening of the exhaust from the cylinders.

15 My invention consists of certain details of construction hereinafter set forth, pointed out in my claim, and illustrated in the accompanying drawings, in which—

Figure I shows a plan view, in section, of 20 one of the cylinders and its attachments; Fig. II shows a vertical sectional view taken on the line 2—2, in Fig. I; Fig. III shows a vertical sectional view taken on the line 25 3—3, in Fig. II; and Fig. IV is a diagram showing the relative positions of the valves and piston in a cylinder and its attachments.

Referring to the accompanying drawings, 30 10 indicates a cylinder, 11 the piston head and 12 the connecting rod. On the outer surface of the cylinder are secured two other, and smaller, cylinders 13 and 14, respectively, the latter extending above the main cylinder 10. Each of these cylinders is provided with a piston head, 15 and 16 respectively, and connecting rods, 17 and 18 respectively. The cylinder 14 (the one extending above the cylinder 10) is provided with a port 19 which opens into the upper portion of the main cylinder 10 and the said cylinder 10 is 35 provided with a port 20, in horizontal alignment with the port 19, which opens into the smaller auxiliary cylinder 13. The cylinder 14 is provided with an intake pipe 21 and the cylinder 13 is provided with an exhaust 40 45 22. The upward extension of cylinder 14, to which the intake pipe is connected, has its top or upper end closed by a removable plug, as shown.

The rod 12 is connected with a crank arm 50 23 on the main crank shaft 24, and the shafts 17 and 18 are connected with their respective crank arms 25 and 26, on the auxiliary crank shaft 27 and the two crank shafts are operated together by the gear wheels 28 and 29

mounted on their respective shafts and 55 geared as desired.

The numeral 30 indicates the water jacket which surrounds the cylinders hereinbefore described, and my motor is designed to be comprised of a multiple of such cylinders. 60

In practical operation the pistons in the auxiliary cylinders all being on one shaft are timed not only for the proper opening of the intake ports and the exhaust ports but also with relation to each auxiliary cylinder on each main cylinder and as their crank shaft which carries the crank arms is geared to the main crank shaft which carries the crank arms from the main cylinder pistons, it is obvious that the admission of 65 70 gas and the exhaust is uniformly timed. As the spark is also timed in the ordinary manner, it is obvious a double timing is thus obtained.

Having thus described my invention what 75 I claim and desire to secure by Letters Patent of the United States is:

A gas engine comprising a main cylinder, and a tangential pair of auxiliary cylinders arranged adjacent each other and constituting intake and exhaust valve casings, an uninterrupted water jacket surrounding the cylinders and extending over the main and exhaust auxiliary cylinder, the intake auxiliary cylinder extending through and above 80 85 the water jacket and having its upper end opened, a closure plug removably secured in the opened upper end of the intake cylinder, an intake pipe connected laterally to extension of the intake cylinder above the water jacket, an outlet pipe connected to the other auxiliary cylinder and extending through the water jacket, the intake and exhaust cylinders communicating with the main cylinder through ports arranged in a common 90 95 plane above the outlet pipe and below the intake pipe, a piston in the main cylinder, valve pistons in the auxiliary cylinders, a main drive shaft connected to the main piston, a single crank shaft having spaced 100 crank portions connected to the valve pistons, and intermeshing gears connecting the shafts.

MICHAEL HACKETT.
